(57) **CLAIM**

The ornamental design for an automotive wheel, as shown and described.

DESCRIPTION

FIG. 1 is a front elevation view of an automotive wheel showing my new design;

FIG. 2 is a rear elevation view thereof;

FIG. 3 is a right side elevation view thereof, the opposite side, the top side, and the bottom side being a mirror image of the shown; and,

FIG. 4 is an isometric view thereof.

In the drawings, the broken lines depict environmental subject matter and form no part of the claimed design.
